HELICAL SPLINE GRINDING MACHINE

James L. Jessup, Detroit, Mich., assignor to Colonial Broach Company, Warren Township, Mich., a corporation of Delaware

Application February 24, 1949, Serial No. 78,211

19 Claims. (Cl. 51—95)

1

This invention relates generally to grinding machines and the like, and more particularly to a helical spline grinding machine.

It is an object of this invention to provide a grinding machine of the aforementioned type in which the lead bar is connected to and disposed below a reciprocating work table so that the overall length of the machine is materially reduced, as compared to machines wherein the lead bar is disposed above the work table, and so that the lead bar is protected against metal chips from the work piece, or other foreign particles which often adhere to lead bars disposed above the work table.

It is a further object of this invention to provide a grinding machine of the aforementioned type, in which the lead bar is connected to the rotating spindle of a work index head, carried by the work table, by means of change speed gearing or the like, so that one lead bar can be used to produce a plurality of different leads on work pieces.

It is a further object of this invention to provide a grinding machine of the aforementioned type, which can be used either to form grind helical involute splines on a work piece or to generate involute helical splines on a work piece.

It is a still further object of this invention to provide in a grinding machine of the aforementioned type, a double acting backlash device which is operably connected to the machine lead bar so as to remove backlash in the lead bar, change speed gearing, and work index head, for both directions of table reciprocation.

It is a still further object of this invention to provide in a grinding machine of the aforementioned type, means for synchronizing the reciprocation of the work table with the operation of the aforementioned backlash device, so that when the table reaches the end of each reciprocating stroke the backlash device will be operated to take the backlash out of the machine in the proper direction prior to the reciprocation of the work table in the opposite direction.

It is a still further object of this invention to provide, in a grinding machine of the aforementioned type, a grinding wheel spindle quill, which is reciprocable in two directions on anti-friction bearings, and feed screws for feeding the quill in both directions, each of which engages and meshes with, so as to feed the quill, grooved anti-friction rollers which are connected with the quill, whereby to eliminate or at least materially reduce friction and backlash in the quill operating mechanism so that the operation and

2

control of the feeding of the grinding wheel is enhanced to provide an extremely accurate and efficient machine.

It is a still further object of this invention to provide a grinding machine of the aforementioned type, having means for directing any hydraulic liquid which may escape from the operating mechanisms of the machine to a sump or trap in the machine base, adjacent to the hydraulic fluid reservoir tank, whereby any sediment in the liquid can settle to the bottom of the sump or trap and can be easily removed therefrom, and whereby in the event there is a considerable leakage of liquid, the overflow of liquid from the sump or trap will flow into the fluid reservoir tank.

It is a still further object of this invention to provide an improved hydraulic circuit and system for operating the movable elements of the grinding machine.

It is a still further object of this invention to provide a grinding machine of the aforementioned type which is efficient in operation, extremely accurate in use, and durable in construction.

These and other objects of this invention will become apparent from the following detailed description taken in conjunction with the accompanying drawings, in which:

Figures 1-A and 1-B, when placed end to end, are longitudinal sectional views of the machine of this invention, with parts broken away in elevation.

Fig. 2 is an enlarged fragmentary sectional view of the structure illustrated in Fig. 1-B, taken along the line 2—2 thereof.

Fig. 3 is an enlarged fragmentary view, partly in section and partly in elevation, of the structure illustrated in Fig. 1-B, taken along the line 3—3 thereof.

with certain parts of the machine illustrated diagrammatically in elevation for purposes of clarity.

Fig. 10 is an enlarged sectional view of the structure illustrated in Fig. 9, taken along the line 10-10 thereof.

Fig. 11 is an enlarged fragmentary sectional view of the structure illustrated in Fig. 9, taken along the line 11-11 thereof.

Fig. 12 is an enlarged fragmentary elevational view of the structure illustrated in Fig. 11, taken along the line 12-12 thereof.

Fig. 13 is a fragmentary sectional view of the structure illustrated in Fig. 11, taken along the line 13-13 thereof.

Fig. 14 is an enlarged fragmentary sectional view of the structure illustrated in Fig. 9, taken along the line 14-14 thereof.

Fig. 15 is an enlarged fragmentary sectional view of the structure illustrated in Fig. 11, taken along the line 15-15 thereof.

Fig. 16 is a view partly in section and partly in elevation of the structure illustrated in Fig. 15, taken along the line 16-16 thereof.

Fig. 17 is an enlarged fragmentary sectional view of the structure illustrated in Fig. 9, taken along the line 17-17 thereof.

Fig. 18 is an enlarged fragmentary side elevational view of the structure illustrated in Fig. 1-B, taken within the circle 18 thereon, with parts broken away in section for purposes of clarity.

Fig. 19 is an enlarged sectional view of the structure illustrated in Fig. 1-A, taken along the line 19-19 thereof.

Fig. 20 is a sectional view of the structure illustrated in Fig. 19, taken along the line 20-20 thereof.

Fig. 21 is an enlarged sectional view of the structure illustrated in Fig. 1-B, taken along the line 21-21 thereof.

Fig. 22 is an enlarged sectional view of the structure illustrated in Fig. 9, taken along the line 22-22 thereof.

Fig. 23 is a vertical section through the work index head shown in Fig. 1-A.

Fig. 24 is a fragmentary sectional view of the structure illustrated in Fig. 23, taken along the line 24-24 thereof.

Fig. 25 is a diagrammatical view of the hydraulic circuit and operating mechanism of the machine of this invention.

Referring now to the drawings, it will be seen that the grinding machine of this invention includes a base or supporting structure 27, which is enclosed by a housing, including side walls 29. A reciprocable work table 31 is slidably supported on the top of the base 27 in ways 33 and 35. A vertical column 37, in which is housed the operating and supporting mechanism for a grinding wheel 38, extends upwardly above the base 27, rearwardly of the reciprocating work table 31, and is supported on the base in any suitable manner. A tail stock 39 for supporting one end of a work piece 40, is adjustably mounted in an inverted T slot 42, on the reciprocable work table 31, in a conventional manner, and includes (Fig. 18) a housing 41, having an axially movable center 44. A shaft 43 is journalled in the housing 41 and carries a worm 47 on the inner end thereof, which meshes with a rack 49, formed on the underside of the center 44. A hand wheel 48 is connected to the outer end of the shaft 43 for operating the latter, and the pointed end of the center engages and supports one end of the

work piece 40, as shown in Figs. 1-A and 1-B. A coolant pump 51 and tank 52 are mounted in the base 27 for supplying coolant to the work piece during the grinding operation in a conventional manner, and a coolant drain trough 53 and passageways 54 are provided in the base for returning used coolant to its reservoir tank.

A work indexing head 55 is rigidly mounted on the work table 31 adjacent one end thereof and in spaced relation to the tail stock 39. The work indexing head is described in detail in the applicant's Patent No. 2,528,753 relating to Improvements in Index Head for Rotary Spindles, and includes generally a housing or base 57 having a sleeve 59 journalled in the rear portion thereof (Figs. 23 and 24). A drive shaft 61 is rotatably supported in the sleeve 59 and the rear end thereof projects outwardly through one end of the housing for connection to suitable gearing, as will be hereinafter described. A second sleeve 63 is supported in the front portion of the housing, in coaxial relationship with respect to the sleeve 59, and a spindle 65 is rotatably supported in the sleeve 63 and has a center 67 detachably connected thereto. An indexing mechanism 68, which includes an indexing plate 69 and a plunger 70 carried on worm gear shaft 71, is supported in the housing 57 for indexing the spindle 65 relative to the drive shaft 61. The spindle drive shaft 61, indexing mechanism 68 and spindle 65 are inter-connected by means of differential gearing 72, so that the spindle 65 can be driven by the drive shaft 61 independently of the indexing mechanism and so that the spindle can be indexed relative to the drive shaft 61 by the indexing mechanism 68, even while the spindle is being driven by the drive shaft. The spindle center 67 is adapted to engage the opposite end of the work piece 40 from that engaged by the tail stock center and a dog type clamp 73 is provided, in a conventional manner, for driving the work between the spindle and tailstock centers, as will be hereinafter described.

In order to reciprocate the work table 31, a hydraulic piston and cylinder unit 75 is provided, which includes a movable cylinder 77 and a pair of stationary adjacent pistons 79 and 81, which have outwardly extending hollow piston rods 83 and 85, respectively, connected thereto. The rods 83 and 85 have openings 86 in the walls thereof, adjacent their respective pistons, for a reason which will appear. The outer ends of the piston rods 83 and 85 are threadably connected in block-like plates 87, which in turn are supported in vertical ribs or bulkheads 89 of the base 27. Fluid conduits 91 and 93 are threadably connected to the block-like plates 87 so as to communicate with the outer ends of the piston rods 81 and 83 respectively. The conduits 91 and 93 are connected to a work table reversing valve 95, in a manner which will be hereinafter described. A hydraulic fluid reservoir or tank 99 is built into the bottom of the base 27 and a hydraulic pump 101 is supported above the tank 99 and has a suitable intake pipe or conduit 103 extending into the tank.

The right hand end of the cylinder 75, as viewed in Fig. 1-B, extends through an angle bracket 105 and has an annular shoulder 109 on the end thereof, which is connected to the vertical leg of the bracket 105, by any suitable means. The upper horizontal portion of the bracket 105 is connected to the under side of the reciprocating work table 31 by suitable means such as key 111 and cap screws 107. The pis-

ton rod 85 extends outwardly through a suitable seal and end cap in the cylinder, for connection to the plate 81. The opposite end of the cylinder 75 is slidably supported in the vertical portion of an angle bracket 111, which is similar to the bracket 105, and the piston rod 83 extends outwardly through a suitable seal 113 and end cap 115 in the cylinder end for connection to its plate 81. The upper horizontal portion of the angle bracket 111 is connected to the under side of the reciprocable work table 31 by any suitable means such as cap screws 107 and a key 117. Therefore, when hydraulic fluid is forced under pressure into, for example, the piston rod 85, it flows through the rod 85 and into the cylinder through the opening 86, adjacent its inner end, while any fluid in the opposite end of the cylinder 75 flows out of the cylinder through the opening 86 adjacent the inner end of the piston rod 83, through the piston rod 83 and back to the control valve 95 through the conduit 93, thence to the oil reservoir 99. The induction of pressurized liquid into one piston rod or the other causes the movement of the cylinder in one direction or the other, and when the cylinder and work table have reached one end of their stroke, their direction of movement is reversed, in a manner which will be hereinafter described, so that reciprocation of the work table is obtained. Thus, by hydraulically operating the cylinder 75 the work table is reciprocated and the work piece 40, the indexing head 55 and tailstock 39 are moved back and forth across the base.

In order to control the length of the reciprocating strokes of the work table 31, a rack 123 is mounted on the front face of the work table and has a pair of stop members 125 movably positioned thereon. The stops 125 carry pawls 127 which are adapted to engage the rack teeth in any predetermined position. The stops 125 also carry dogs 129 thereon and the position of the dogs can be adjusted by means of adjusting screws 131. The dogs 129 are adapted to engage a lever element 133 on the reversing valve 95 so as to cause a shifting of the mechanism in the valve 95 which, will in turn reverse the flow of hydraulic fluid from one piston rod 83 or 85 to the other, in a manner which will be herein-after described. An additional stop 137 is carried on the rack 123 and is adapted to engage the upper end of a lever or finger member 139, which is connected to a shaft 141 (Fig. 2). The shaft 141 is rotatably supported in the base and has a depending finger or lever 143 connected to the opposite end thereof. The finger or lever 143 is adapted to engage a plunger 145 of the valve 95, so as to stop the movement of the work table when it is moving from left to right as viewed in Fig. 18. This arrangement permits the table, when it has a grinding wheel dresser thereon, to be moved to a predetermined position, beyond the end of the reciprocating stroke, so as to bring the dresser up to the wheel. This can be accomplished by manually raising dog 129 so that the table will not reverse, but will be stopped when the stop 137 engages the lever element 139. After the dressing operation the reciprocation can again be started by actuating the valve manual control handle 146 and other mechanisms, as will be hereinafter described.

As the grinding machine of this invention is primarily designed to grind helical splines it is provided with means for rotating the spindle in synchronism with the reciprocations of the work

table. The preferred mechanism for this purpose is a helical lead bar element and a cooperating nut element, either one of which may be mounted on the base of the machine and the other rotatably journaled on the table and operatively connected to the indexing head spindle. In the illustrated embodiment of the invention the lead bar is rotatably journaled in the table brackets, and the nut element is mounted on the base of the machine. As will be hereinafter set forth in detail the machine also incorporates a backlash eliminating device which operates to eliminate backlash in the spindle rotating mechanism. This device operates by rotatably adjusting the position of the nut and lead bar elements in the spindle rotating mechanism.

Thus the machine includes a lead bar 147 which is connected to and disposed beneath the work table 31. The right hand end of the lead bar 147, as best seen in Fig. 1-B, is rotatably supported in the angle member 105 by means of bearings 151 and bearing supporting means 153. The opposite end of the lead bar 147 is rotatably supported in the angle member 111 by means of bearings 157, and projects therethrough, so as to carry a gear 159 on the extreme end thereof, beyond the angle member 111. The lead bar 147 therefore reciprocates with the cylinder 75 and the work table 31. In order to impart rotation to the lead bar during its reciprocation, a pair of longitudinally spaced nuts 159 and 161 are provided, which engage the lead bar 147 and are rigidly connected to the opposite ends of an annular sleeve 163 by means of cap screws 165 (Fig. 5). The sleeve 163 has a gear 167 formed on one end thereof, and the gear 167 meshes with the teeth of a rack 171, which is secured to a member 173, for reasons which will hereinafter appear. The sleeve 163 is rotatably supported in a housing 177 by means of anti-friction bearings 179. The sleeve is secured against longitudinal movement in the housing 179 by means of the gear portion 167 of the sleeve, a nut 181 and thrust bearings 183. Therefore, while the lead bar nuts 159 and 161 are rotatable and adjustable for certain purposes, as will be hereinafter brought out, they are stationary during the longitudinal movement of the lead bar and thereby impart rotation to the lead bar during its movement.

The left hand end of the lead bar 147, as viewed in Fig. 1-A, is connected to the work indexing head drive shaft and rotating spindle 61 and 65, respectively, of the work indexing head 55, through change speed gearing 185, as can be best seen in Figs. 20 and 21. That is, the gear 159 on the end of the lead bar 147 meshes with a gear 187 which in turn is meshed with gear 197. Gears 187 and 197 are rotatably connected to an adjustable arm or bracket 189 by suitable internally disposed bearings. The arm or bracket 189 is journaled at its lower end on a hub member 190, which is secured to the angle member 111, and is adjustably connected to a vertical end wall 191 of the work table 31 by means of a cap screw 193, which extends through an elongated slot 195 in the arm. This assembly forms a reversing device which may be used to change the hand of a part being ground, that is, to produce a right or left hand helix as desired regardless of the number of gears in the change gear system or the hand of the master lead bar. It should be noted that the gears 159, 187 and 197 all have the same number of teeth and therefore comprise an idler gear system whose ratio is always

1/1 and thus does not enter into the calculations of the change gearing to produce a desired lead on the part being produced. By loosening cap screw 193, the arm 189 can be pivoted to permit meshing either gear 187 or 191 with the interchangeable gearing represented by gears 199, 201, 203, and other gears to be hereinafter described. One of an infinite variety of gearing is represented in Fig. 19, in which gear 199 meshes with the small gear 201 of a gear cluster 203, and the large gear 205 of the cluster meshes with the small gear 207 of a gear cluster 209. The large gear 211 of the cluster 209 meshes with a gear 213, which is carried on the end of the indexing head drive shaft 61. The gear clusters 203 and 209 are journaled on a fan shaped supporting bracket or arm 219, and the arm or bracket 219 is pivotally supported on the drive shaft supporting hub portion 221 of indexing head housing. The mounting shafts or bolts 214 for the gear clusters 203 and 209 extend through elongated slots 215 and 217 respectively in the bracket 219, so that various sized gears may be employed when desired. The arm or bracket 219 is provided with additional slots so that the size and number of the change speed gears can be changed. It will thus be seen that the lead bar is connected to the drive shaft and rotating spindle of the indexing head through change speed gearing and any desired speed ratio between the lead bar and the rotating spindle can be obtained by changing the gear ratio. In this way the necessity of having more than one lead bar is eliminated and a plurality of different leads may be formed on a work piece through a variance of the change speed gearing arrangement.

In order to protect the lead bar and the other operating mechanisms of the machine, which are disposed beneath the work table from dust, dirt, chips, or other foreign particles, a canvas strip 225 is provided. One end of the strip 225 is connected to a sheet metal housing 227 which is disposed over the change speed gearing 185 and extends outwardly and over a roller 228 which is supported on the base adjacent one end thereof by means of a bracket 229. The opposite end of the canvas strip is wound around a drum 231 which is supported on the bracket 229 by a pair of narrow canvas belts 233. The drum 231 is composed of a shaft 232, an outer shell and two end plates. Shaft 232 extends beyond the end plates far enough to allow the canvas straps 233 to be attached to it. If the canvas strip 225 is rolled up on the large diameter of the drum before the canvas straps are attached to the central shaft 232, the entire drum can be supported by the two canvas straps. When the table moves to the right (as shown in Fig. 1-A) the canvas strip will be unrolled from drum 231 and in so doing will cause the canvas straps 233 to be rolled up on the shaft 232. As the table moves to the left the weight of the drum will cause it to unroll the canvas straps from around the shaft and reroll the canvas strip on the drum. Thus the strip is always under a tension proportional to the weight of the drum assembly. A similar canvas strip 225 is provided on the opposite end of the work table and the canvas strip 225 is wound in the same manner as that previously described and similar parts of this mechanism are marked with primed numbers corresponding to the like mechanism at the opposite end of the machine. Therefore, the lead bar of this machine is protected at all times against the ingress of foreign materials which would

tend to cause wear or damage thereto. Likewise, it will be appreciated that as the lead bar is disposed beneath the work table, rather than above the base and longitudinally outwardly of the work table, as in most conventional machines, the length of the machine is materially reduced and is approximately forty percent shorter than machines which have the lead bar mounted above the base, and on the work table.

In the event that there is any leakage of the hydraulic fluid from the reciprocating cylinders 75 or any drippage from the lead bar 147, the base is provided with a pair of longitudinally spaced and longitudinally extending, inwardly and downwardly inclined plates 231 and 239, which direct such fluid into a trap or sump 241, which surrounds and is adjacent to the reservoir tank 99. The side walls 29 of the base are provided with plugged apertures 243 at the bottom thereof, adjacent to the sump or trap 241 so that any sediment in the leaked fluid can be easily removed. In the event that there is a considerable amount of leakage in the hydraulic system, there is no danger of the fluid overflowing and spilling onto the floor, due to the fact that when the level of the liquid in the sump or trap rises to the level of the top of the reservoir tank 99, it will flow into the reservoir tank and will be recirculated through the hydraulic system. Any sediment in the leaked fluid will have had a chance to settle to the bottom of the sump or trap before the fluid overflows into the tank. In this way a neat and efficient manner of handling any fluid which may leak is provided, without the danger of any foreign particles or sediment getting back into the hydraulic system.

One of the most prevalent difficulties in grinding machines has been that of inaccuracies due to backlash which is set up in the lead bar, the work indexing head and the connections therebetween. It will be appreciated that with the machine of this invention, due to the change speed gearing connection between the lead bar and the spindle of the indexing head, a great amount of backlash would ordinarily be present. This machine is therefore provided with a double acting backlash device 245, which removes all of the backlash between the lead bar nuts and the rotating spindle 65 of the work indexing head. This machine is, therefore, extremely accurate and the work piece will be properly indexed, by an exact predetermined amount, during the reciprocation of the work table. This machine thus grinds work pieces much more accurately than has been heretofore possible.

The double acting backlash device 245 is shown in detail in Figs. 3 through 8, and comprises a housing 247, which includes a cylinder 249, having polygonally shaped members 251 sleeved on and welded to each end thereof. End caps 253 are connected to each end of the housing 247, by means of cap screws 255, which extend through and are threadably connected to the sleeved members 251. The housing 247 is connected to a slide 257 by means of cap screws 259. The slide 257 is slidably mounted in a dovetail way 261 of a plate member 263. The plate member 263 in turn is connected to a slide 265 by means of cap screws 267, and the slide 265 is slidably mounted in a dovetail way 269 in a plate member 271 forming a part of the base of the machine. The slides 257 and 265 may move relative to each other for purposes which will hereinafter appear. The slide 257 is a part of the rack supporting member 175, which is connected to the rack 171.

In this way when the housing 247 and the slide 257 move, the rack 171 will likewise be moved so as to rotate the gear 167 formed on the end of the sleeve member 163, which in turn will rotate the lead bar nuts 159 and 161, in order to eliminate backlash, as will hereinafter appear. Disposed within the cylinder 249 are a pair of end to end piston rods 275 and 277. The inner end of the piston rod 275 is formed with a threaded end portion 279 which fits into a threaded aperture 281 in the inner end of the rod 277 and the two rods are immovably connected together in an end to end relationship by means of taper pin 283, so that in effect, a single piston rod is provided. The adjacent inner ends of the rods 275 and 277 are externally threaded at 285 and 287 respectively and the threads 285 and 287 are of the opposite hand. A pair of pistons 291 and 293 are disposed in the cylinder 249 and the inner end of the piston 291 is provided with a threaded aperture 295 in which the threaded end 285 of the rod 275 is threaded. The piston 293 is provided with a similar threaded aperture 297 in its inner end, which is threaded onto the threaded portion 287 of the rod 277. The pistons 291 and 293 are bore fitting pistons within the cylinder 249 and are provided with a plurality of piston rings or seals 301, in a conventional manner.

The piston rods 275 and 277 extend outwardly through their respective pistons and through bores 303 which are provided in inwardly extending shank portions 305 of the end caps 253, as well as through seals 307 and seal retainers 309, which are carried in the outer ends of the end caps 253. The inner ends of the shank portions 305 of the end caps 253 extend inwardly through apertures 309' in the rear or outer wall of the pistons 291 and 293, so that the cylinder 249 and shank portions 305 are free to slide longitudinally with respect to the pistons. The outer periphery of each end cap shank 305 is formed with a plurality of circumferentially spaced spline spaces 310, for a reason that will hereinafter appear, and the wall of each piston which defines apertures 309' has a pair of opposed splines 312 which slidably engage a pair of the spline spaces 310 for retaining the pistons against rotation, but permitting relative axial movement between the end caps and pistons. The movement of the cylinder relative to the pistons 291 and 293 is limited by the shank portions 305 of the end caps. For example, when the cylinder moves to the left, the extent of its movement is limited by the engagement of the shoulder of the piston 293, adjacent the threaded aperture 297, with the shank portion 305 of the end cap 253. The same piston and shank abutment will occur when the pistons move to the right and the piston 291 will engage the adjacent shank portion 305.

The outer end of the piston rod 277, outwardly of the housing 247, is journalled in an aperture 311, in a rib or plate 313 of the base (Fig. 3), and a knurled handle or knob 315 is secured to the outer end of the rod for turning the same. The outer end of the rod 275 extends outwardly beyond the opposite end of the housing 247, and is rotatably supported in a journal block or bracket 317. The block 317, in turn, is supported on, and rigidly connected to, the plate 263 by means of cap screws 319. The plate 263 is, of course, in turn rigidly connected to the second slide 265. The outer end of the piston rod 275, while being rotatably supported on the bracket or block 317,

is held against axial movement with respect thereto by means of collar members 321 and nuts 323. Therefore, when the knurled handle 315, on the end of the rod 277, is rotated, pistons 291 and 293 will be rotated and will move axially within the cylinder 249. As the threaded portions on the inner ends of the piston rods are of the opposite hand, the pistons will be either moved toward or away from each other so that the extent of relative movement between the cylinder and pistons can be adjustably controlled.

The backlash device is connected in the hydraulic system of the machine in a manner which will be hereinafter described, so that it will operate only at the end of each reciprocating stroke of the table. A hydraulic passageway head or block 325 is attached on one end of the cylinder 249, and a similar block 325' is secured to the opposite end of the cylinder 249. The block 325 and cylinder end member 251 are provided with a fluid passageway 327, which has a conduit 329 connected to the outer end thereof, and which communicates at its inner end with an aperture 331 in the wall of cylinder 249. The conduit 329 is connected to either the pressure side of the valve 95 or to the tank side thereof, in accordance with the positioning of certain valve means which will be hereinafter described. The wall aperture 331 is disposed adjacent to but forwardly of the rear portion of the end cap shank 305, so that when the piston 293 moves rearwardly or outwardly, that is toward the left as viewed in Fig. 6, the aperture 331 will be closed by the piston. Outwardly or rearwardly of the passageway 327, the block 325 and cylinder end member 251 are provided with a passageway 333, which extends parallel to the passageway 327 and which has its outer end normally closed by a check valve which includes a ball 335 and a spring 337, and its inner end communicating with an aperture 338 in the wall of cylinder 249. The free end of the spring 337 extends through the cylinder wall and abuts a portion of the end cap 253, outwardly or rearwardly of the shank portion 305. The passageway 327 is connected with the passageway 333, outwardly of or beyond the ball 335, by means of a passageway 339. The passageways 327 and 333 are connected, inwardly of the check valve by means of a passageway 341, which communicates with and extends at right angles to the passageway 327, a passageway 343 which communicates with and extends at right angles to passageway 333, and a passageway 345 which connects passageways 341 and 343.

55 A metering pin 347 is threadably connected to the block 325 and secured by a lock nut 349. The inner end of the pin extends into the passageway 345. The outer end of the pin 347 is provided with a knurled handle 350 to permit the pin to be threaded into or out of the block 325 so as to adjust the position of the inner end of the pin in the passageway 345 and thereby control the flow of fluid through the passageway 345. The block 325' on the opposite end of the cylinder is constructed in the same manner as the block 325 previously described, and corresponding parts of the block 325' are indicated by primed numbers corresponding to the numbers employed in connection with the description of the block 325.

60 In operation, when it is desired to actuate the backlash device, the piston rod handle 315 is turned so as to position the pistons 291 and 293 in a desired relationship with respect to the cylinder and the shank portion 305 of the cylinder end caps; that is, the pistons are positioned so that

65

70

75

their maximum movement is limited in accordance with the amount of the backlash which must be removed in the lead bar nuts, the gearing between the lead bar and the work indexing head spindle.

During the operation of the machine, when the reciprocating table reaches one end of its stroke, valve mechanisms, as will be hereinafter described, will be actuated to cause, for example, fluid to flow under pressure into the conduit 329, and if the cylinder aperture 331 is not closed by piston 293 the hydraulic fluid will flow through the block passageway 327, the cylinder aperture 331, and into the end of the cylinder. However, if the cylinder aperture 331 is closed by the piston, the fluid will flow through the block passageway 339 and will unseat the ball 335 from its seat, and then flow through passageway 333 and cylinder aperture 338 and into the cylinder end. The fluid will then flow through the end cap shank notches 310 into the piston 293, and cause the cylinder to move to the left, as viewed in Fig. 6. As the cylinder moves to the left any fluid in the opposite end of the cylinder, behind the piston 291, will flow out of the block passageway 327' and through the conduit 329' to the tank until such time as the cylinder aperture 331' is covered by the piston 291. When this occurs the fluid will flow out through passageway 333' into passageway 343' through passageways 345' and 341', and then into passageway 327', conduit 329' and valve 95, thence to tank 99. By adjusting the metering pin 347', any desired dash pot effect may be obtained to prevent the piston from slapping against the cylinder end cap. The amount of the dash pot effect or the cushioning which is obtained will, of course, depend on the manner in which the metering pin is adjusted in the passageways 345'.

When the cylinder moves to the left the slide 257 will move in its dovetail way 261 in plate 263 and will cause the rack 171 to rotate gear 167 and the lead bar nuts 159. The lead bar nuts 159 will be rotated until all of the backlash has been taken out between the nuts and the lead bar, as well as the change speed gearing and the gearing in the work indexing head. It will also be understood that the cylinder can be moved in the opposite direction to remove backlash in the opposite direction, in the same manner as described, except that the conduit 329' becomes the pressure inlet conduit and the conduit 329 becomes the return tank line. A conduit 350 is connected to one of the conduits 329 or 329' so as to direct fluid onto the lead bar 147 and keep the same lubricated. It will thus be appreciated that this simple backlash device solves a problem that has been perplexing the grinding industry for many years and permits the use of change speed gearing between the lead bar and the spindle of the work indexing head, which heretofore could not be done. It will also be appreciated that when the reciprocating table reaches each end of its stroke, the backlash device will be operated in the proper direction to remove backlash. Thus, this backlash device is capable of operating in two directions so as to continually take the backlash out of all the gearing for both directions of table reciprocation, irrespective of the number of gears in the change gear train and hand of lead bar used. The operating sequence of the device will be hereinafter described.

In order to grind the desired form on the work piece 40 the grinding wheel 38 is mounted on the vertical column 37 for both vertical and horizon-

tal movement by means of supporting structure 351 (Fig. 11). The supporting structure 351 includes sleeve 353 which extends vertically within the column 37 and which is formed with flange portions 355 on the lower end thereof. The flange portions 355 are recessed on the opposite sides of the sleeve at 357 and a portion of a ball bearing race 359 is disposed in each of the recesses 357 and connected to the flanged portion of the sleeve 351 by means of cap screws 361. Each race 359 is in the form of an elongated block which extends horizontally across the vertical column 37 and has a V-shaped raceway 363 in the outer face thereof for locating and supporting a plurality of longitudinally spaced anti-friction ball bearings 365. An outer race 367 is provided adjacent each of the inner races 359, and the outer race 367 has a V-shaped raceway 369 in the inner face thereof, for supporting the ball bearings 365. Each outer race 367 is disposed in a recess 371 of a block member 373, and is connected to the block member 373 by means of cap screws 375. The block member 373 is in turn connected to a stationary portion 377 of the vertical column 37 by any suitable means, such as cap screws 379. In this way the vertical column or sleeve 353 is supported for longitudinal movement from left to right in the vertical column 37, as shown in Fig. 9. A longitudinally extending tapered gib 381 is disposed between the outer face of the outer bearing race 367, on the left hand side of the sleeve 351, as viewed in Fig. 11, and the inner face of the block member 373, and the tapered gib can be adjusted so as to adjust the bearing race relationship, on both sides of the sleeve 353, in order to take out any play or binding friction between the balls and the races, and so as to provide an anti-friction mounting for the sleeve 353 in the vertical column.

40. In order to assure that the ball bearings 365 will properly roll in their races and will not pile up because of any foreign particles which might lodge between the ball bearings and their races, the outer faces of the sleeve flange portion 355, 45 on each side of the sleeve, and the inner face of each vertical column portion 377 has a rack 385 connected therewith. A gear 387 is disposed between the racks 385 and engages both racks so as to insure that the inner and outer bearing races, 50 will move relative to each other in the desired manner at all times, irrespective of any foreign particles which might tend to affect the operation of the ball bearings. The gear 387 is disposed above the ball bearings 365 and is connected to the races in any suitable manner such as by screw 55 389. It will, therefore, be appreciated that this anti-friction mounting of the sleeve 351 permits cross feed movement of the grinding wheel 38 in a simple and efficient manner.

60. Mounted concentrically within the vertical sleeve 351, is a cylindrically shaped quill 391. The quill 391 is mounted for vertical movement in the sleeve 351 by means of three circumferentially spaced sets of anti-friction bearings 393. 65 Each of the bearings 393 includes an inner race 395, which is disposed in a vertically extending recess 397 in the peripheral wall of the quill 391, and is connected thereto by means of cap screws 399. The outer race 401 of each bearing 393 is disposed in a vertically extending recess 403 in the wall of the sleeve 351 and is connected thereto by means of cap screws 405. Each of the outer races 401 is formed with a V-shaped notch or raceway 407 for locating and guiding a plurality of vertically spaced anti-friction ball bearings 75

409. The outer face of one of the inner bearing races is formed with a V-shaped raceway 411 for the reception of the ball bearings 409, while the outer faces of the inner races of the other two bearings are not notched. The bearing 393 in which both the inner and outer races are provided with V-shaped raceways, has a tapered gib 413 disposed between the outer face of the outer race 401 and the inner face of the sleeve recess 403, which can be adjusted to take any play or binding friction out of all three bearings simultaneously, in generally the same manner as the tapered gib 381, previously described. In this way a simple adjustment is provided for the bearings to insure the proper bearing relationship between the inner and outer bearing races and the balls.

A seal 415 is disposed between the flange portion of the sleeve member 351 and the bearings 393, adjacent the lower end thereof, to prevent the ingress of foreign particles. In order to protect the longitudinally extending bearings from foreign particles or the like, a plate 417 is secured to the under side of the block 373 and a plate 419 is secured to the under side of the flange portion of the sleeve 353. A longitudinally extending plate 421 has one end thereof connected between the bottom of the sleeve 353 and the plate 419 by means of screws 423, while the opposite edge of plate 421 is slidably disposed in a slot 425 in the inner face of the plate 417. Therefore, when the sleeve 351 moves relative to the block 373, the plate 421 will slide in the slot 425, and in conjunction with a canvas dust curtain hereinafter described, will at all times prevent the ingress of foreign particles into the longitudinal bearings.

A spindle supporting member 427, is provided for supporting a helical screw type hydraulic motor 428, which drives a spindle 429 on which the grinding wheel 38 is mounted. The member 427 is formed with an annular horizontal flange 431 intermediate the upper and lower ends thereof, and with an upwardly projecting hub portion 433. The hub portion 433 is disposed in a central aperture 435, in the bottom wall of the quill 391, while the upper face of the spindle flange 431 abuts the under side of the quill bottom wall. A block 437 is positioned in a recess 439 in the upper face of the bottom wall of the quill 391, and has a central threaded aperture 441 for the reception of the threaded end of a bolt 443, which extends upwardly through the hub portion 433. The head of the bolt 443 abuts the underside of the hub portion 433, above a recess 445 in the spindle supporting member 427. The bolt 443 therefore, when threaded into the block aperture 441, supports the spindle 427 on the quill 391. By loosening the bolt 443, the spindle may be rotated relative to the quill 391 so that the grinding wheel may be rotated to any helix angle during the grinding operation.

In order to determine the angular position of the grinding wheel with respect to a zero point, for purposes of dressing the latter, a protector scale 447 is provided, which extends around the outer periphery of the lower end of the quill 391, and a zero mark or point is provided on the outer periphery of the flanged portion 431 of the spindle supporting member in such a position that it indicates the point at which the plane of the grinding wheel is parallel to the plane of motion of the reciprocating work table. A plunger 449 is slidably mounted in an aperture 451 in the supporting member flange portion 431, and the upper end of the plunger is adapted to

be manually moved into an aperture 453 in the bottom wall of the quill. The aperture 453 in the quill and the plunger 449 in the spindle supporting member are so located than when the plunger is moved into the quill aperture the zero mark on the spindle will be in alignment with the zero mark on the quill scale, thus providing a rapid means of returning the grinding wheel spindle to the dressing position. In order to rotate the spindle to the desired helix angle, the plunger must be pulled out of engagement with the quill.

A pair of stops 455 are secured to the quill scale 447 and the lower end of the quill 391 by any suitable means, such as cap screw 457, and a stop 459 is adjustably mounted on the outer periphery of the spindle supporting member flange portion 431, by means of a T-headed bolt 461 which has the head portion thereof disposed in a T-slot 463 in the flange portion 431. The stop 459 overlaps the stops 455 and is adapted to engage either of the latter, at any desired helix angle in order to provide a means of rapidly resetting the grinding wheel to the grinding position after the dressing operation.

If it is desired, therefore to grind with the grinding wheel 38 at a predetermined helix angle, the bolt 443 is loosened, the plunger 449 is pulled downwardly and the spindle is rotated until the zero mark thereon is in alignment with the desired angular mark on the quill scale 447. The spindle stop 459 is then adjusted to engage one of the stops 455 on the quill so that thereafter when it is desired to rotate the spindle relative to the quill, at the same angle for further grinding operations, the spindle can be turned until the stops 459 and 455 abut, at which time the predetermined angular position will have been reached. When this angular position is reached the bolt 443 is tightened and grinding can begin. When it is desired to return the grinding wheel to its original position for further dressing operations, the bolt 443 is again loosened and the spindle swung back to its original position and the plunger pushed up into the quill aperture 453, so as to lock the spindle stop in its original position. The grinding wheel is then in position for further dressing operations.

It is at certain times, such as when involute splines are being generated by the machine, desirable to lock the quill 391 against vertical movement. The arrangement shown herein for locking the quill against vertical movement comprises an annular split ring 471, which is positioned in a notch or recess 473 provided in the sleeve 351 behind the outer bearing races 401, and the free ends of the split ring 471 are formed with outwardly extending lug or ear portions 475 and 476 which project into a recess 477 in the flange portion 355 of the sleeve 353. Extending around the lugs or ears 475 and 476 is a housing 479, as shown in Fig. 15, which has the upper and lower walls thereof rigidly connected to the lug or ear 475 by means of cap screws 481 and pins 483. The outer side face of the lug or ear 476 is cut back on an angle at 485, and a cam block 487 has its inner cam face complementally inclined and engaging the inclined face of the ear 476, while its outer flat face engages the inner face of the side wall of the housing 479. The upper threaded end of a rod 489 is threaded into a tapped aperture 491 in the cam block 487. The shaft 489 extends downwardly through the lower wall of the housing 479 and is journaled in a bearing 493 which is connect-

ed to the lower wall of the housing. The lower portion of the shaft, below the bearing 493, is enlarged and extends downwardly through an aperture 497 in the lower flange portion sleeve 353, and carries a handle 499 on the lower end thereof, below the sleeve 353. When the handle 499 and the rod 489 are turned, the cam block 487 will move vertically to thereby either force the split ring ear 476 toward the stationary ear 475 or away from it, in accordance with the direction of rotation. Thus, by turning the handle 499 in one direction, the split ring may be tightened around the quill so as to lock the same against vertical movement, and by turning the handle in the opposite direction the split ring will permit the quill to move freely on its vertical bearings.

In order to feed the sleeve 353 horizontally, a feed mechanism is provided which includes a shaft 501 (Fig. 17), which is journalled in the side wall 503 of the vertical column 37, by means of suitable bearings 505 and bearing retainers 507. The shaft 501 carries a hand wheel 509 on the outer end thereof and has a worm 511 mounted thereon, within the vertical column. The inner end of the shaft 501 is journalled in the column by means of bearings 513 mounted in a web 515 of the vertical column. The worm 511 meshes with a worm gear 517, which is mounted on a feed screw 519, adjacent the forward end thereof, as can be seen in Fig. 9. The forward end of the feed screw 519 is journalled in the front portion of the column by bearing 520, and extends rearwardly adjacent to the sleeve 353 and is engaged, intermediate the ends thereof, by three circumferentially spaced, annularly grooved rollers 521. The grooved rollers are journalled on and connected to the sleeve 353 by means of bolts 523 and suitable supporting bracket means 525, in a manner which will be hereinafter more fully described in detail, in connection with another set of similar rollers. The rollers are formed with annular thread forms which are made with a slightly different included angle than the angle of the threads on the feed screw 519. The rollers eliminate friction as much as possible in the feed screw mechanism, which would tend to cause the feed screw to wind up and have backlash when the hand wheel 509 is rotated by the operator, thereby eliminating inaccuracies which are so prevalent in most cross feed mechanisms. When the hand wheel 509 is turned by the operator, the rotation of the feed screw 519 will cause the grooved rollers 521 and the grinding wheel supporting sleeve 353 to move transversely and horizontally with respect to the reciprocating work table 31. The feed screw 519, rearwardly of the grooved rollers 521, is journalled in a web 527 of the column, by means of bearings 529 and suitable bearing retainers 531. The rear portion of the feed screw is connected to a series of change speed gears and certain other gearing, for reasons which will hereinafter appear.

In order to feed the quill 391 upwardly and downwardly in the vertical column, a feed mechanism is provided which includes a vertically extending feed screw 535 (Fig. 9), which is journalled on the spindle supporting structure 351, in any suitable manner. The vertical feed screw engages three circumferentially spaced annularly grooved rollers 537, which are formed with annular thread forms of a slightly different included angle than the angle of the feed screw threads, as previously described for the cross feed screw.

The circumferentially spaced grooved rollers 537 are journalled on a bracket 539 by means of bolts 541 and bearings 543 (Fig. 14). The bracket 539 in turn is connected to the quill 391 by any suitable means, such as cap screws 545, as shown in Fig. 13. Therefore, as the feed screw 535 is rotated, the engagement thereof with the teeth of the grooved rollers 537, will cause the quill to move vertically on its bearings. A worm gear 551 is connected to the lower end of the vertical feed screw 535 (Fig. 21), and meshes with a worm 553, which is mounted on one end of a shaft 555, which in turn is supported in a stationary housing portion 557 on the lower end of the sleeve 351 by means of suitable bearings 559. A hand wheel member 563, in the form of a housing, is connected to one end of the shaft 555, selectively through either a rapid traverse feed arrangement or a normal traverse feed arrangement, as will now be described.

A sleeve 565 is held on the outer end of the shaft 555 by means of a nut 567 and a key 568. The inner end of the sleeve 565 has one element 569 of a dog clutch thereon. The outer end of a sleeve bearing 571 is rotatably supported on the outer periphery of the sleeve 565 and is connected to the housing or hand wheel member 563 by any suitable means such as a dog point set screw 573. Another element 575 of the dog clutch is provided on the inner periphery of sleeves 571, adjacent the inner end thereof, and is adapted to engage and mesh with the dog clutch element 569. A collar 577 is sleeved in the shaft 555 and slidably keyed to the hand wheel member 563. The outer end of the collar abuts the inner face of the sleeve 565. The collar 575 is provided with a pair of longitudinally spaced sockets or notches 579 and 581, for a use which will hereinafter appear. The hand wheel member 563 is, therefore, supported for axial movement relative to the shaft 555. A spring pressed ball 583 is mounted in the hand wheel member 563 for engagement in the collar notches 579 or 581. The extreme inner end of the hand wheel member 563 has its outer periphery rotatively engaging and supported by a flanged wall 585 of the housing 557 and has its inner periphery toothed at 587 to provide a ring gear. A sun gear 589 is connected to the shaft 555 by any suitable means such as the taper pin 591, and meshes with a plurality of planetary gears 593 which are journalled on suitable cap screws 595 and sleeve bearings 597 attached to housing 557. The planetary gears mesh with both the sun gear 589 and the ring gear portion 587 of the hand wheel member 563, in the position shown in Fig. 21. An annular ring 599 is connected to the outer periphery of the hand wheel 563 and carries a scale thereon which operates with a pointer 601 on the housing 557 to indicate the rotative position of the hand wheel.

When it is desired to operate the vertical feed screw with the normal traverse feed arrangement, the hand wheel member 563 is pulled outwardly so that the spring pressed ball 583 is disposed in the collar notch 579, and so that the dog clutch elements 575 and 569 are in engagement. When the hand wheel member 563 is pulled outwardly, the ring gear portion 587 thereof is moved out of engagement with the planetary gears and the drive from the hand wheel member is through the dog clutch elements and sleeve 565 directly to the shaft 555. When a rapid traverse is desired, the hand wheel 563 is pushed inwardly, as shown in Fig. 21, so that the ring

gear portion 587 thereof engages the planetary gears 593, and so that the dog clutch elements 575 and 569 are out of engagement. When the hand wheel is in this position the spring pressed ball 583 is seated in the collar notch or socket 581. When the hand wheel is rotated the drive is through the planetary gears and sun gear to the shaft 555, so that rapid traverse is obtained.

In order to protect the quill and operating mechanisms in the vertical column from chips or other foreign particles, a canvas strip 601 is provided which has one end connected to a roller mechanism 602, which is mounted in the lower rear portion of the vertical column and the other end connected to a similar roller mechanism 603, which is mounted in the upper front portion of the column. The strip extends down the front of the column around a rod 605 and is attached to the front edge of the sleeve 351. The rear curtain is attached in a similar manner. As both roller mechanisms are alike, as shown in Fig. 22, only one will be described in detail. The mechanism 603 includes a roller 606, journalled on a shaft 607 by means of bearings 609 and the opposite ends of the shaft 607 are supported in wall portions 611 of the vertical column 37. The roller 606 is hollow and has a coil spring 613 disposed therein, which surrounds the portion of the shaft 607 which extends through the roller. One end of the spring 613 is connected to a collar 615 which in turn is connected to the shaft 607. The opposite end of the spring 613 is connected to a collar 617 which is connected to the roller by means of cap screws 619. Therefore, the canvas strip and roller can unwind when the spindle supporting structure moves in one direction, and when so doing will wind up the spring 613. When the spindle supporting structure moves in the opposite direction, the roller will be rotated by the spring and will re-wind the canvas strip thereon, thereby always maintaining the canvas strip under tension but permitting the same to move with the grinding wheel spindle supporting structure at all times so as to continuously prevent the ingress of any foreign materials into the operating mechanisms in the vertical column.

In order to give the machine the maximum of utility, it is desirable that it be constructed so that helical splines, having an involute or other similar form, can be generated on a work piece. In order that the generation of such forms may be accomplished, this machine is shown as being provided with additional mechanism, as will be presently described. It is to be understood that such mechanism need not be employed in the machine if the latter is to be used for form grinding only. However, this mechanism is preferably employed so that the machine can be used for both generating and form grinding operations. The mechanism which permits the generating of involute or other similar forms includes a gear 631, which is connected to the cross feed screw 519, adjacent the rear end thereof, in the vertical column. The gear 631 meshes with a plurality of change speed gears 633, which may be identical with the change speed gears disposed between the lead bar and the drive shaft of the work indexing head, as previously described, and shown in Figs. 20 and 21. The lowermost change speed gear 633 is carried on a horizontal stub shaft 635, which is suitably journalled in the rear portion of the column. A bevel gear 637 is also carried by stub shaft 635, and meshes with a complementary bevel gear 639 on the upper end of a vertical shaft 641, which is journalled in the ma-

chine. The shaft 641 extends downwardly into the base 27, rearwardly of the double acting backlash device 245. A bevel gear 643 is carried on the lower end of the shaft 641, which meshes with a complementary bevel gear 645 on the rear end of a shaft 647 which is journalled in the base 27. The forward end of the shaft 647 is threadably connected to the journal block or bracket 317, which rotatably supports the rear end of the backlash device piston rod 275. The shaft 647 carries, intermediate the ends thereof, a gear or ratchet wheel 651 which is adapted to be actuated by a pawl 653, which is pivotally mounted on a head 654 on the upper end of a piston rod 655. The piston rod 655 extends upwardly from and forms a part of a hydraulic piston and cylinder unit 657 which is connected in the hydraulic circuit of the machine as will be hereinafter described. The piston and cylinder unit 657 is adapted upon actuation to move the piston rod 655 upwardly so as to cause the pawl 653 to rotate the gear 651 and the shaft 647 a predetermined amount. The rotation of the shaft 647 will cause axial movement of the journal block bracket 317 which is mounted on the secondary slide 265 of the backlash device. Therefore, when the shaft 647 is rotated, the entire backlash device and the lower slide 265 will move and will cause the lead bar to be rotated and indexed due to the actuation of the lead bar nuts 159 by the gear 161 and the rack 171 which is connected to the backlash device. This movement of the lead bar will cause the spindle 65 of the work index head, and the work piece to be indexed by a predetermined amount. At the same time the rotation of the shaft 647 will cause rotation of the grinding wheel feed screw 519 through the change speed gears 633 so that the grinding wheel feed screw and the work index head spindle are simultaneously indexed by predetermined amounts during the reciprocation of the work table, thereby permitting an involute or other similar form to be generated on the work piece. Due to the fact that change speed gearing is interposed between the shaft 647 and the feed screw 519, the indexing relationship between the feed screw and the lead bar can be varied by any amount so that not only true involute splines can be generated but also other similar types of forms. The operation of this generating mechanism will become more apparent from the following detailed description of the hydraulic system of the machine.

The hydraulic system for operating the machine is illustrated diagrammatically in Fig. 26. In Fig. 26, the operating cylinder 77 for the reciprocable work table 31 is shown in the middle of its movement of a stroke toward the left. Thus, the reciprocating work table is in the middle of its stroke from right to left. When the table and cylinder are in the aforementioned moving position, the pump 101 is being driven by motor 661 and hydraulic fluid is being pumped through conduit 663 into a passageway 665 in the body of the main reversing valve 95.

When the machine is started the metering shaft 667 in the valve body is turned so as to open passageways 669 in the valve and permit the flow of fluid therethrough. Fluid flows from the passageway 665 to passageway 669, past a hydrostatic pressure compensator 671 which maintains a constant flow rate of the fluid. The reversing spool 673 of the valve has been shifted to the right in a manner which will be hereinafter described, and the fluid is flowing into the spool bore 675 and through passageway 677 and con-

duit 93 so as to cause the movement of the cylinder to the left. The spool 673 has been shifted to the right by hydraulic fluid which flowed from valve body passageway 665 upwardly through passageway 681 and into bore 683, in which a movable pilot spool 685 is mounted.

As the pilot spool 685 has been shifted to the right by the engagement of lever 133 by the table dog 129, the fluid from the passageway 681 has flowed out of the spool bore 683 through a passageway 687 and into conduit 689. The fluid flowed through the conduit 689 to a four way rotary type pilot valve 691. The pilot valve 691 has been rotated by an actuator 693, which in turn is operated by an arm 695 on the piston rod 655 of the piston and cylinder unit 657, so that the fluid has flowed through the valve 691 to a conduit 697. The fluid passed through the conduit 697 into the valve body of a pressure control valve 699, and into a conduit 701, connected to the conduit 697 ahead of the pressure valve 699. The fluid in conduit 699 initially flowed through a one way valve 703 and conduit 705, into a passageway 707 in the valve body 709 of a reversing valve 711 for the double acting backlash device 245. The fluid flowed through the passageway 707 into a bore 713 in the valve body, in which a spool 715 has been shifted to the right, as will be hereinafter described, and out through a passageway 717 and conduit 329, so as to shift the cylinder 249 of the backlash device to the left, as illustrated.

After the backlash device was shifted, fluid pressure was built up in the conduits 705, 701 and 697, and the passageway 721 in the valve body of the pressure valve 699, to which conduit 691 is connected. The pressure valve 699 has a vertically movable piston 723 therein, which is normally held in a down position by means of a spring 725. When the piston is in its down position the flow of liquid through the valve 699 is prevented as the return passageway 727 of the valve is blocked by the upper portion of the piston. However, the fluid under high pressure in the valve passageway 721 has flowed downwardly through a U-shaped passageway 727 and moved the piston 723 upwardly against the action of the spring 725, thereby opening the valve passageway 727 and permitting the fluid to flow out of the valve 699 through conduit 731. The fluid then flowed through conduit 731, into a passageway 733 in the main reversing valve 95, through passageway 733, past a small ball check valve 735 and into the left hand end of the main spool bore 675 so as to shift the spool 673 to the right, as illustrated. The fluid in the right hand end of bore 675 is returned to the tank through passageway 736 and a suitable conduit. It will of course be understood that, in certain installations the valve 711 may be eliminated and the backlash device 245 directly connected in the main cylinder and pressure control valve conduits, without affecting the operation or function of the machine.

The spool 715 of the backlash device reversing valve 711 was shifted to the right, as illustrated, by means of fluid which flowed through the conduit 689, conduit 737, through a manually operable four way rotary type pilot valve 739, which is similar in construction to the pilot valve 691 previously described, through conduit 741, into the left hand end of the backlash device reversing valve 711. The fluid from the right hand end of the reversing valve bore 713 passed out through a conduit 743 and back through a pilot valve 745,

which is similar to the pilot valve 739, through conduit 747, conduit 749, into the right hand end of the main reversing valve pilot spool bore 683, through the bore 683 and out through a drain passageway 753 to the reservoir tank 99. It will be appreciated that the pilot valves 739 and 745 are manually set to the positions shown and left in these positions unless it is desired to reverse the operation of the backlash device relative to the piston and cylinder unit, such as where a lead of the opposite hand is to be used.

A four way rotary type pilot valve 755 is also provided adjacent the pressure valve 691 and fluid from the piston and cylinder unit 657 is returned to the tank 99, when the piston is pushed upwardly by spring 757, through a conduit 758 and through the pilot valve 755 to a conduit 759 which is also connected to conduit 749.

When the reciprocating work table reaches the end of its stroke the reversing lever or dog 133 of the main reversing valve will be actuated so as to shift the pilot spool 685 to the left, thereby blocking off the flow of fluid to the spool bore 683 through the passageway 681, and causing the fluid to flow through the passageway 681 to a horizontal passageway 761 and into the right hand end of the bore 683, so that the fluid will be pumped through conduit 749, conduit 759 and pilot valve 755, thereby moving the piston of the piston and cylinder unit 657 downwardly. As the piston rod 655 moves downwardly the arm 695 actuates the pilot valve actuator 693 so as to rotate the pilot valves 691 and 755, thereby causing fluid to flow from the conduit 758 through the pilot valve 755 to a conduit 765, which in turn is connected to passageway 721' of a pressure valve 699', which is identical in construction with the pilot valve 699, and a conduit 767, which bypasses the valve. The piston will then move upwardly, causing the shaft 647 to be rotated by the ratchet 651 so as to index the cross feed screw 519 and the rotating spindle 65 of the work index head, as previously described.

The fluid will initially flow through conduit 767 and one way valve 771 to a conduit 705. In the meantime, the spool of the backlash device valve 711 has been shifted to the left, due to the flow of fluid through conduit 749, conduit 741, pilot valve 745, and conduit 743, and into the right hand end of the bore 713 of the valve 711. The spool 715 will then be shifted to the left and the fluid in the left hand end of the bore will return to tank through conduit 741, pilot valve 739, conduits 737 and 699, passageway 687 in the main reversing valve body 95, pilot spool bore 683, and drain passageway 771. The fluid therefore, flows from conduit 705 into the passageway 707 of the valve 711, through the valve bore 713, valve passageway 779, and conduit 329', so as to shift the cylinder of the backlash device 245 in the opposite direction. The fluid in the opposite end of the backlash device will return to tank through conduit 329, valve passageway 717, valve bore 713, valve passageway 791, and a conduit 783 connected to the tank 99.

After the backlash device has been shifted and sufficient fluid pressure built up in the valve 711, conduits 705 and 767, and passageway 721' of pressure valve 699', the piston 723' will be raised so as to permit the flow of fluid through outlet passageway 727', conduit 785, passageway 787 in the right hand end of the main reversing valve body 95, past ball check 789 and into the right hand end of the reversing spool bore 775, so as to shift the reversing spool 673 to the

left. The fluid in the left hand end of the bore 675 will then return to tank through passageway 697 and conduit 93. The cycle is then completed and continued reciprocating movement of the work table 31 is obtained as the dogs 129 engage the reversing lever 133 of the main reversing valve.

The grinding wheel spindle shaft 429 is being rotated simultaneously by means of a hydraulic motor 428, which is connected to the tandem pump 101 through a conduit 801, a manually operable four-way valve 803, and conduits 805 and 807. The direction of rotation of the hydraulic motor and spindle can be reversed by the valve 803, if desired or necessary in order to have the grinding wheel rotating in the proper direction, so as not to throw chips or the like into the operator's face. The grinding wheel will rotate generally in the same direction during the grinding of any one work piece, but for different grinding operations it may be desirable to have the grinding wheel rotate in the opposite direction, for the reasons pointed out above.

It will thus be seen that with this machine the work table is continuously reciprocated and at the end of each stroke the backlash device 245 is actuated so as to take up all backlash through the lead bar 147 and change speed gearing to the rotating spindle 65 of the work index head, prior to the reciprocation of the work table in the opposite direction. It will also be appreciated that the arrangement heretofore described properly sequences the movements of all of the elements of the machine so that the proper coordination between the parts is obtained and the efficient results of the machine achieved. It will also be noted that when it is desired to generate involute splines or the like by grinding, the indexing of the grinding wheel cross feed screw and the rotating spindle 65, through the lead bar, is achieved by the movement within the piston and cylinder unit 657 which in turn actuates the ratchet on the shaft 641.

As has been previously pointed out, the machine may be built and constructed for use only as a form grinding machine and the generating mechanism illustrated in Fig. 9, omitted. If the machine is built in this latter manner, the pilot valves 691 and 755 are eliminated and the conduit 747 is connected directly to conduit 697 while conduit 759 is connected directly to conduit 765.

In order to stop the reciprocating work table 31 at any point in a reciprocating stroke, for dressing purposes, as previously described, the stop plunger 145 is connected with a normally closed valve 791, which is mounted in the main reversing valve body 95, adjacent to the right hand end of the pilot spool bore 683. When the stop 137 engages the lever 139, the valve 791 is opened to permit the flow of fluid from valve passageway 753 through passageway 793, through the normally closed valve bore 795, passageway 797, bore 799 of a normally open valve 801 and passageway 803 to the bottom of the hydrostat 671. Since the operation of the hydrostat depends on a balance between the inlet pressure and a pressure on the bottom thereof, this balance is destroyed by the flow of fluid to the bottom thereof and if it opens the hydrostat and allows all of the fluid from the pressure side of the valve to return to the reservoir tank instead of to the operating cylinder, thereby stopping the operation of the reciprocable table. When the normally open valve 801 is pushed inwardly, it temporarily closes off the flow of fluid through

passageway 797 to the hydrostat and when the manual operating handle 146 of the reversing valve 95 is actuated in the opposite direction the stop 137 moves away from the lever 139 so as to permit the plunger 145 and its valve 791 to move to the closed position, thereby allowing the normal reciprocating cycle to be continued.

It will thus be appreciated that the machine of this invention can be used for either form grinding or generating helical splines on a work piece, and that the accuracy of the machine has been greatly increased due to the removal of the backlash throughout the machine and due to the anti-friction mounting of the movable elements. It will also be appreciated that the operation of this machine is fully automatic, thereby rendering the machine simple to operate, efficient and durable in use, and generally much more satisfactory and efficient than any similar grinding machine heretofore devised.

What is claimed is:

1. A grinding machine including a reciprocable work table, means for reciprocating said work table, a lead bar element, a lead bar nut element 25 threadedly connected with said lead bar element for rotation relative thereto, means rotatably supporting said lead bar element, means connecting said reciprocating means to one of said elements so that movement of said reciprocating means rotates said one element, a work indexing head having a rotatable spindle on said table, means connecting said indexing head spindle to said one element so that rotation of said element rotates said spindle, actuatable 30 double acting backlash means connected with the other of said elements and including means normally retaining said other element against rotation, and means for actuating said backlash means to cause rotation of said other element so as to remove backlash between said other element and said indexing head spindle.

2. A grinding machine including a reciprocable work table, means for reciprocating said work table, a lead bar element, a lead bar nut element 45 threadably connected with said lead bar element for rotation relative thereto, means rotatably supporting said lead bar element, means connecting said reciprocating means to one of said elements so that movement of said reciprocating means rotates said one element, a work indexing head having a rotatable spindle on said table, change speed gearing connecting said indexing head spindle to said one element so that rotation of said element causes rotation of said spindle, actuatable double acting backlash means 50 connected to the other of said elements and including means normally retaining said other element against rotation, and means for actuating said backlash means to cause rotation of said other element for eliminating backlash between said other element and said indexing head spindle.

3. A grinding machine including a reciprocable work table, means for reciprocating said work table, a lead bar element, a lead bar nut element 55 threadably connected with said lead bar element for rotation relative thereto, means rotatably supporting said lead bar element, means connecting said reciprocating means to one of said elements so that movement of said reciprocating means rotates said one element, a work indexing head having a rotatable spindle on said table, means connecting said indexing head spindle to said one element so that rotation of said element rotates said spindle, actuatable 60 double acting backlash means connected with the other of said

elements and including means normally retaining said other element against rotation, and means automatically operable at the end of each reciprocating stroke of said table for actuating said backlash means to cause rotation of said other element so as to remove backlash between said other element and said indexing head spindle, in accordance with the direction of reciprocation of the work table to follow.

4. A grinding machine including a reciprocable work table, means for reciprocating said work table, a lead bar element, a lead bar nut element threadably connected with said lead bar element for rotation relative thereto, means rotatably supporting said lead bar element, means connecting said reciprocating means to one of said elements so that movement of said reciprocating means rotates said one element, a work indexing head having a rotatable spindle on said table, change speed gearing connecting said indexing head spindle to said one element so that rotation of said element causes rotation of said spindle, and backlash means connected with the other of said elements and including means normally retaining said other element against rotation, and means automatically operable at the end of each reciprocating stroke of said table for actuating said backlash means to cause rotation of said other element so as to remove backlash between said other element and said indexing head spindle, in accordance with the direction of reciprocation of the work table to follow.

5. A grinding machine including a reciprocable work table, means for reciprocating said work table, a lead bar element, a lead bar nut element threadably connected with said lead bar element for rotation relative thereto, means rotatably supporting said lead bar element, means connecting said reciprocating means to one of said elements so that movement of said reciprocating means rotates said one element, a work indexing head having a rotatable spindle on said table, means connecting said indexing head spindle to said one element so that rotation of said element rotates said spindle, actuatable backlash means connected with the other of said elements and including means normally retaining said other element against rotation and causing rotation of said other element upon actuation of said backlash means to remove backlash between said other element and indexing head spindle in both directions of table reciprocation, means for automatically operating said backlash means at the end of each reciprocating stroke of said table, and means for positively retaining said table at the end of each stroke until said backlash means has been actuated.

6. A grinding machine including a reciprocable work table, means for reciprocating said work table, a lead bar element, a lead bar nut element threadably connected with said lead bar element for rotation relative thereto, means rotatably supporting said lead bar element, means connecting said reciprocating means to one of said elements so that movement of said reciprocating means rotates said one element, a work indexing head having a rotatable spindle on said table, means connecting said indexing head spindle to said one element so that rotation of said element rotates said spindle, actuates backlash means connected with the other of said elements including means normally retaining said other element against rotation and causing rotation of said other element upon actuation of said backlash means to remove backlash between said

other element and indexing head spindle in both directions of table reciprocation, and means for temporarily retaining said table at the end of each stroke and actuating said backlash means prior to the subsequent movement of said table.

7. A grinding machine including a reciprocable work table, a hydraulic unit disposed beneath said work table and including a cylinder element having a piston element thereon, one of said elements being movable and connected to said work table and the other of said element being stationary so that the actuation of said element which is connected to said table causes movement of the latter, a lead bar member, a lead bar nut member threadably connected with said lead bar member for rotation relative thereto, means rotatably supporting said lead bar member, means connecting said movable hydraulic element with one of said members, a work indexing head on said table having a rotatable spindle, means connecting said spindle to said one member so that rotation of said one member causes rotation of said spindle, actuatable double acting backlash means connected with the other of said members and including means normally retaining said other member against rotation and causing rotation of said other member upon actuation of said backlash means so as to eliminate backlash between said other member and said indexing head spindle.

8. A grinding machine including a reciprocable work table, means for reciprocating said work table, a lead bar element, a lead bar nut element threadably connected with said lead bar element for rotation relative thereto, means rotatably supporting said lead bar element, means connecting said reciprocating means and one of said elements so that movement of said reciprocating means rotates said one element, an indexing head on said table having a rotatable spindle, change speed gearing connecting said spindle with said one element so that rotation of said one element causes rotation of said spindle, actuatable double acting backlash means connected with the other of said elements normally retaining said other element against rotation, but upon actuation of said backlash means rotating the same to eliminate backlash between said other element and said indexing head spindle, and means for temporarily retaining said table at the end of each stroke and actuating said backlash means prior to the subsequent movement of said table.

9. A grinding machine including a reciprocable work table, means for reciprocating said work table, a lead bar element and a lead bar nut element, one of said elements being connected with said reciprocating means, a work indexing head having a rotatable spindle on said table, means connecting said indexing head spindle to one of said elements, a backlash device including a stationary piston and a reciprocable cylinder, and means connecting said backlash cylinder to the other of said elements so that said backlash device will remove backlash between said other element and indexing head for both directions of table reciprocation.

10. A grinding machine including a reciprocable work table, means for reciprocating said work table, a lead bar element and a lead bar nut element, one of said elements being connected with said reciprocating means, a work indexing head having a rotatable spindle on said table, means connecting said indexing head spindle to one of said elements, a double acting backlash

device including a reciprocable cylinder having a stationary piston therein automatically operable at the end of each table stroke to remove backlash between the other of said elements and said index head spindle, means connecting said reciprocable cylinder to said other element, and means for coordinating the operation of said work table and backlash device so that said work table will not start its return stroke until after said backlash device has removed the backlash between said other element and said indexing head spindle in the direction corresponding to the stroke of said work table to follow.

11. In a metal working machine a housing, a vertically extending element, antifriction bearing means supporting said element in said housing for reciprocation in one plane, a second element, antifriction bearing means supporting said second element on said first element for reciprocation in a plane disposed substantially at right angles to the plane of reciprocation of the first element a member adapted to carry a metal working tool and connected with said second element, a feed screw in said housing for moving said member in each of the aforementioned two planes, and a plurality of grooved rollers journaled on said elements and meshing with each of said feed screws for moving said member in said directions, so as to provide anti-friction engagement between said feed screws and elements and prevent backlash during reciprocation of said elements.

12. In a grinding machine, a reciprocable work table, means for reciprocating said table, a spindle on said table having its axis extending parallel to the direction of table reciprocation, means for rotating said spindle in synchronism with the reciprocal movements of said table, a grinding wheel spindle supported above said work table for movement transversely of said table, a feed screw for feeding said grinding wheel spindle in said transverse direction and means for indexing both said spindle and said feed screw a predetermined amount at the end of each reciprocating stroke of said work table.

13. In a grinding machine, a reciprocable work table, means for reciprocating said table, a lead bar element and a lead bar nut element disposed below said table, means connecting said reciprocating means to one of said elements so that movement of said reciprocating means rotates said one element, an indexing head on said table having a spindle, means connecting said indexing head spindle to said one element so that rotation of said one element rotates said spindle, a grinding wheel spindle supported above said work table for movement transversely of said table, a feed screw for feeding said grinding wheel spindle in said transverse direction, a double acting backlash device including a reciprocable cylinder having a stationary piston therein, means connecting said reciprocable cylinder to the other of said elements, a shaft having one end connected with said stationary piston, a gear on said shaft, ratchet means for rotating said shaft, means connecting said shaft to said grinding wheel spindle feed screw, and means for actuating said ratchet at the end of each reciprocating stroke of said table so as to cause said one element and grinding wheel feed screw to be indexed a predetermined amount.

14. In a grinding machine a reciprocable work table, means for reciprocating said table, a lead bar element and a lead bar nut element disposed below said table, means connecting said recipro-

cating means to one of said elements, an indexing head on said table having a rotatable spindle, means connecting said indexing head spindle to said one element, so that rotation of said one element rotates said spindle, a grinding wheel spindle supported above said work table for movement transversely of said table, feed screw means for feeding said grinding wheel spindle in said transverse direction, and means for indexing both said spindle and said feed screw means a predetermined amount at the end of each reciprocating stroke of said work table including change speed gearing connected with said feed screw means so that the indexing ratio between said spindle and said feed screw may be varied.

15. In a grinding machine a reciprocable work table, means for reciprocating said table, a lead bar element and a lead bar nut element disposed between said table, means connecting said reciprocating means to one of said elements so that movement of said reciprocating means rotates said one element, an indexing head on said table having a rotatable spindle, change speed gearing connecting said indexing head spindle to said one element so that rotation of said one element rotates said spindle, a grinding wheel spindle supported above said work table for movement transversely thereof, feed screw means for feeding said grinding wheel spindle in said transverse direction, a double acting backlash device including a cylinder member having a piston member therein, one of said members being retained against axial movement, means connecting the movable member to the other of said elements, change speed gearing connected with said feed screw means, means operatively connected with said stationary backlash member and said change speed gearing, and means for indexing said last means a predetermined amount at the end of each reciprocating stroke of said work table.

16. Motion transmitting mechanism including two interconnected members, a double acting backlash device including a cylinder connected with one of said members, a pair of longitudinal end to end piston elements disposed in said cylinder, piston rod means extending longitudinally through said pistons and cylinder connected to the other of said members, stationary means rotatably supporting one end of said piston rod means, means closing the opposite end of said cylinder and forming abutments for limiting relative movement between said pistons and cylinder, means for adjusting the position of said pistons relative to said cylinder abutments so that the relative movement between said piston and cylinder may be adjustably controlled, and fluid inlet and outlet means adjacent each end of said cylinder for communication with the interior of said cylinder beyond said pistons whereby when pressurized fluid is supplied to one end of said cylinder, said cylinder will move in one direction relative to said piston elements and when fluid is supplied to the other end of said cylinder said cylinder will move in the opposite direction with respect to said piston elements.

17. A double acting backlash device including a cylinder, means slidably supporting said cylinder, a pair of longitudinal end to end piston elements disposed in said cylinder, and having threaded apertures of opposite hands therein, piston rod means extending longitudinally through said pistons and cylinder and having a threaded portion of one hand thereon for threadably engaging one of said pistons and a threaded portion

of the opposite hand for threadably engaging the other of said pistons, stationary means rotatably supporting one end of said piston rod means whereby when said piston rod means is rotated said piston elements will move toward or away from each other and relative to said cylinder, means closing the opposite ends of said cylinder and forming abutments for limiting relative movement between said pistons and cylinder and fluid inlet and outlet means adjacent each end of said cylinder for communicating with the interior of said cylinder beyond said pistons whereby when pressurized fluid is supplied to one of said cylinder, said cylinder will move in one direction relative to said piston elements and when fluid is supplied to the other end of said cylinder the cylinder will move in the opposite direction with respect to said piston elements.

18. A double acting backlash device including a movable cylinder, a pair of longitudinally end to end piston elements disposed in said cylinder and having threaded apertures of opposite hands therein, axially stationary piston rod means rotatably supported in said cylinder and extending longitudinally through said piston and cylinder, said piston rod means having a threaded portion of one hand thereon for threadably engaging one of said pistons and a threaded portion of the opposite hand for threadably engaging the other of said pistons, whereby when said piston rod means is rotated said piston elements will move toward or away from each other and relative to said cylinder, means closing the opposite ends of said cylinder and forming abutments for limiting relative movement between said pistons and cylinder, and fluid inlet and outlet means adjacent each end of said cylinder for connection with the interior of said cylinder adjacent each end thereof, so that when pressurized fluid is supplied to one end of said cylinder said cylinder will move in one direction relative to said piston elements, and when said fluid is supplied to the other end of said cylinder the cylinder will move in the opposite direction with respect to said piston elements.

19. A double acting backlash device including a movable cylinder, a pair of longitudinally end to end piston elements disposed in said cylinder and having threaded apertures of opposite hands therein, axially stationary piston rod means rotatably supported in said cylinder and extend-

ing longitudinally through said pistons and cylinder, said piston rod means having a threaded portion of one hand thereon for threadably engaging one of said pistons and a threaded portion of the opposite hand for threadably engaging the other of said pistons, whereby when said piston rod means is rotated said piston elements will move toward or away from each other and relative to said cylinder, means closing the opposite ends of said cylinder and forming abutments for limiting relative movement between said pistons and cylinder, fluid inlet and outlet means adjacent each end of said cylinder for connection with the interior of said cylinder adjacent each end thereof, so that when pressurized fluid is supplied to one end of said cylinder said cylinder will move in one direction relative to said piston elements, and when said fluid is supplied to the other end of said cylinder the cylinder will move in the opposite direction with respect to said piston elements, and adjustable dash pot means adjacent each end of said cylinder for providing a controlled dash pot effect at the end of each stroke or movement of said cylinder relative to said piston elements.
